UNITED STATES PATENT OFFICE.

BENJAMIN S. ATWOOD, OF SOUTH ABINGTON, MASSACHUSETTS.

MACHINE FOR MATCHING BOARDS.

SPECIFICATION forming part of Letters Patent No. 307,739, dated November 11, 1884.

Application filed May 4, 1883. (No model.)

To all whom it may concern:

Be it known that I, BENJAMIN S. ATWOOD, of South Abington, in the county of Plymouth and State of Massachusetts, have invented certain Improvements in Machines for Matching Boards, of which the following description, in connection with the accompanying drawings, is a specification.

This invention has for its object the cutting of a groove in the edge of one board and a tongue on the edge of another board at one and the same time, and an improved method of applying glue to the tongue on one side of a board, which is afterward to be inserted 10 in the groove formed in the edge of another board; and it consists in mounting the feed-rollers used in a machine embodying my invention in spring-boxes; in the gear for driving the feed-rollers so that they shall bear 15 their whole length upon the board operated upon and hold it down on the frame whatever the thickness of the board may be; a guide-table at the feed end of the machine, so that when a board is placed in the machine it will 20 be fed automatically; in fixing at the delivery end of the machine a glue-pot heated by steam, in which a wheel revolves, and over which the board passes as it leaves the machine and receives on its tongued side an even coating of 25 glue; in a gage fixed to a cross-bar on the machine, whereby the cutters, when taken out to be sharpened, can be replaced, or another set put on, so that they will cut a groove or tongue of exactly the same size as that already cut, 30 and in hinging the frame carrying the feed-rollers so that it can be raised when required to adjust the cutters.

Referring to the accompanying drawings, Figure 1 is a plan or top view of a machine 40 embodying my invention. Fig. 2 is a side elevation of the same. Fig. 3 is an elevation of the delivery end. Fig. 4 is an enlarged view of the gage. Fig. 5 is a section of the rim of the wheel for gluing the tongue.

45 A is the main frame; B, the upper frame, hinged at one end to the frame A by bolts C and held down at the other end by bolt D.

E is a feed or guide table provided with guides F, the surfaces of which correspond 50 with the surfaces of guides G on the upper frame, B.

H H are friction-rollers, which project slightly beyond the surface of the guides G.

I I are the feed-rollers, the journals of which work in boxes K on the frame B, and the feed-rollers I are kept up to their work by means of spiral springs L, the tension of which is regulated by means of set-screws M. In Fig. 1 the cover of one of the boxes is removed so as to show the springs L. By having the journals at both ends of the feed-rollers carried in the boxes K and the tension of the springs regulated, an even pressure is exerted upon the board passing between the feed-rollers I and the friction-rollers H.

55 N is a shaft fitted at one end with a driving-pulley, P, to which motion is communicated from any convenient source.

On the shaft N is mounted the cutter-carriers Q. On the other end of the shaft N is a small 60 pulley, R, from which motion is communicated to the shaft S by belt T, passing around pulley U. The other end of the shaft S carries the pinion V, which gears into a cog-wheel, W, on the shaft X, on which is mounted two bevel-wheels, Y Y, that gear into other bevel-wheels, 65 Z Z, on short shafts a a, carried in bearings on the beams b b.

In the center of the short shafts a a are pivoted the pinions c c, which gear into cog-wheels 70 d d, which communicate motion to the spindles of the feed-rollers I I through universal joints e e. The spindles of the feed-rollers are square at their lower ends and fit into corresponding holes formed in the upper boss of the upper 75 universal joints, so that when the frame B is raised the ends of the spindles will draw out of the bosses. The object of the universal joints is to allow the feed-rollers to accommodate themselves to different thicknesses of 80 85 boards.

On the bar f, Fig. 1, are mounted the gages. (Shown on an enlarged scale in Fig. 4, which shows one of the gages and a portion of the bar f.) This gage consists of an adjustable base-piece, g, provided with a slot through which a set-screw, g', passes, to hold the same in position on the bar f.

95 h h' h" are three sliding pieces provided with slots, through which screws i i' i" pass for holding them in position upon the base-piece g.

100 When it is desired to remove the cutters to

be sharpened, one of them is first brought opposite to the gage and the sliding pieces $h' h''$ pushed so as to touch the knife-edge of the cutter. The sliding pieces are then clamped down by means of the screws $i' i''$, and thus held firmly until it is desired to replace the cutters, the knife-edges of which are then again placed so as to touch the sliding pieces $h' h''$ and then clamped in position. After all the cutters have thus been set the screw g' is loosened and the base-piece g (and with it the sliding pieces $h' h''$) is drawn back out of the way.

j is a glue-pot fixed at the delivery end of the machine, and is formed with a space, k , at the bottom, into which steam is admitted by the pipe l , for the purpose of heating and keeping the glue in a fluid state.

m is a shaft carried by suitable bearing on the glue-pot. On this shaft is mounted a wheel, n , having a fixed rim, n' , on one side and an adjustable rim, n'' , on the other side, as shown in Figs. 1 and 5. The space between the two rims is adjusted to the width of the tongue, being cut so that as the board passes over the wheel an even coating is applied entirely over the edges of the board and tongue. The shaft m is caused to rotate by means of a cog-wheel, p , and pinion q , the shaft of the latter carrying the pulley r , which is driven by power from any convenient source.

It will be seen that while one set of cutters is cutting the tongue the other set is cutting the groove.

What I claim, and desire to secure by Letters Patent, is—

1. In a machine for matching boards, the combination, with the automatically-adjustable feed-rollers I , provided with spindles having angular lower ends, of the universal joints e , provided with angular holes in their upper bosses, and mechanism connecting said universal joints with the driving-shaft, substantially as described, whereby motion is imparted to said feed-rollers in whatever position they may be, and whereby said rollers may be disconnected from the driving mechanism, as set forth. 35

2. In a machine for matching boards, the combination, with the transverse bar f and the cutters borne by the cutter-carriers Q , of the gages consisting of base-pieces g , set-screws g' , sliding pieces $h' h''$, and set-screws $i' i''$, substantially as and for the purposes described. 45

3. In a machine for matching boards, the combination, with the glue-pot, of a glue-carrying wheel journaled in said pot, provided on one side of its periphery with a fixed rim and on the other side with an adjustable rim, substantially as described, whereby said wheel 55 may be adjusted to boards having tongues of different thicknesses, as set forth. 60

BENJAMIN S. ATWOOD.
